US0D1037252S

(12) **United States Design Patent** (10) **Patent No.:** **US D1,037,252 S**
(45) **Date of Patent:** **** Jul. 30, 2024**

(54) **COMPUTING INPUT DEVICE**

(71) Applicant: **Microsoft Corporation**, Redmond, WA (US)

(72) Inventors: **John Helmes**, Limburg (NL); **Aditha May Adams**, Seattle, WA (US); **Simon Cameron Dearsley**, Bellevue, WA (US); **Go Osaki**, Shenzhen (CN); **Hongshan Sun**, Shenzhen (CN)

(73) Assignee: **Microsoft Corporation**, Redmond, WA (US)

(**) Term: **15 Years**

(21) Appl. No.: **29/837,965**

(22) Filed: **May 10, 2022**

(51) LOC (14) Cl. **21-01**

(52) U.S. Cl.

USPC **D14/388**; D21/333

(58) **Field of Classification Search**

USPC D14/218, 356, 383, 388, 391, 396, 398, D14/400, 401, 405, 406, 412, 413, 414, D14/415, 420, 426, 427, 407; D21/324, D21/325, 329, 331, 332, 333; D13/168

CPC A63F 13/00; A63F 13/24; A63F 13/92; A63F 13/98; G06F 3/011; G06F 3/014; G06F 3/017; G06F 3/033; G06F 3/0338

(74) Attorney, Agent, or Firm — Banner & Witcoff, Ltd.

(57) **CLAIM**

The ornamental design for a computing input device, as shown and described.

DESCRIPTION

FIG. 1 is a front perspective view of a computing input device showing our new design;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The uneven length broken lines depict portions of the computing input device that form no part of the claimed design.

1 Claim, 8 Drawing Sheets
